CLAIM

The ornamental design for a body for refrigerator, as shown and described.

DESCRIPTION

FIG. 1 is a front perspective view of the body for refrigerator showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view in a condition that the multi-storage part has been protruded forward by sliding;

FIG. 9 is a front view of FIG. 8;

FIG. 10 is a rear view of FIG. 8;

FIG. 11 is a left side view of FIG. 8;

FIG. 12 is a right side view of FIG. 8;

FIG. 13 is a top plan view of FIG. 8;

FIG. 14 is a bottom plan view of FIG. 8; and,

FIG. 15 is a top perspective view showing the design in a state of use.

The broken lines depict portions of the body for refrigerator that form no part of the claimed design.
